CLAIM

The ornamental design for a six pack tote apparatus, as shown and described.

DESCRIPTION

FIG. 1 is a front perspective view of a six pack tote apparatus showing our new design;

FIG. 2 is a front elevational view thereof.

FIG. 3 is a top plan view thereof.

FIG. 4 is a right side elevational view thereof.

FIG. 5 is a bottom plan view thereof.

FIG. 6 is a perspective view thereof with bottles inserted.

FIG. 7 is a front elevational view thereof.

FIG. 8 is a top plan view thereof.

FIG. 9 is a right side elevational view thereof, the left side elevational view being identical; and,

FIG. 10 is a bottom plan view thereof.

The broken line showing of stitching, bottles, edge piping, and handle opening is for illustrative purposes only and forms no part of the claimed design.
